UNITED STATES PATENT OFFICE

2,196,430

DEVICE FOR THE REGULATION OF THE OIL
FEED IN OIL FURNACES

Edwin Sprenger, Zurich, Switzerland

Application October 20, 1937, Serial No. 170,084
In Germany October 21, 1936

3 Claims. (Cl. 251—132)

My invention relates to devices for the regulation of the oil feed in oil furnaces and particularly in such oil furnaces in which a preheating bed consisting of refractory fire-bricks is provided through which the combustion air sweeps from below and against which several oil-jets from a plurality of burners are directed from the top.

It is important that the fuel that has to be atomised by steam should descend from above uniformly on the preheating bed occupying the grate or bottom area of the fire box, this being effected with the aid of the several burners already mentioned.

As the oil must accordingly be conducted to several consumption spots if a uniform spraying of the preheating bed is to be attained, the invention provides for a control member with several valves regulated conjointly, though adjustable independently, by which control member the calculated amount of oil is delivered to the several consumption points. As the burners have to be subject to a common control but must not all be supplied with equal amounts of fuel if the best distribution of fire in the fire box is to be reached, it becomes possible by means of this control member to measure the amounts of fuel supplied to the various burners, even when operating, if necessary, and to balance these amounts against each other until the best adjustment is obtained, although of course the control rendered necessary by the momentary load condition of a locomotive or such like must be applied to all burners conjointly.

In the accompanying drawing a controlling device according to my invention is illustrated.

Fig. 1 shows partly in section the controlling device while

Fig. 2 is a section on the line I—I in Fig. 1.

Referring now to Figs. 1 and 2 the device for regulating the feed of oil has a cylindrical casing 101 equipped with fastening flanges 201. This casing 101 is closed at one end by a cover 301 through which passes a supply pipe 401. At its other end this casing 101 is closed by a cover 501 through which also passes a similar pipe 601. The purpose of this duplicate pipe arrangement is to ensure a supply under all circumstances and, in certain cases, to be able to connect up with two storage containers. On the casing 101 several outlets are provided in one line, and each of these outlets is equipped with a screwed socket 71 to which is tightly secured from without, by means of a union 91, a pipe 81 leading to a consumption point. The internal mouth of each socket 71 is in the form of a valve seat while in its interior it possesses a tubular guideway 108 having inflow apertures 111 at its side. Along this guideway 108 a member 121 slides perforated axially and provided with a screw thread. Into the sliding member 121 a valve spindle 131 is screwed carrying on its lower extremity a valve cone 141. Openings are provided in the casing 101 opposite the outlets and each opening is closed by a screw plug 151 which has in its interior a cavity 161 into which the valve spindle 131 projects. Each plug 151 is provided at its inner end with a perforated disc 171 through which passes the valve spindle 131. Between the sliding member 121 and the disc 171 is fitted a pressure-spring 181 by which the valve cone 141 is mounted on the valve spindle 131 is pressed down on the valve seat in the socket 71. In order to permit readjustment without elaborate dismantling when the valve seat or the valve cone 141 has become worn, the plug 151 has a screwed hole in it that is closed by a screw 191. After this screw 191 has been removed, the upper extremity of the valve spindle 131 which is provided with a slot, becomes accessible and by rotation the valve spindle 131 in the slide member 121 may be readjusted. For each outlet in the casing 101 there is a flange 208 at right angles to the outlet and having a perforation through which a bolt or pin 211 can move. This bolt or pin is threaded and is held in the flange 208 by means of a perforated screw 221 having an internal thread and serving to close the bore in the flange 208. A packing seal is arranged between the screw 221 and the flange 208, while the bolt 211 is maintained in position by means of a lock-nut 241. For purposes of protection a completely enclosing hood or cap 251 is screwed on to the flange 208. A bearing-piece 261 is connected with the bolt 211, so that the bolt can rotate relatively to it, and to this bearing-piece 261 are hinged two levers 271 each having a slot 281. These levers 271 are disposed on either side of the sliding member 121 and are connected with the latter by pins 291 screwed into the sliding member 121 and with their extremities resting in the slots 281. In the casing 101 there is mounted a shaft 308 which is journaled at one end in the inside of the cover 501 and at the other end in the cover 301. On the outer extremity of this shaft 308 is mounted a control lever 311, while within the casing 101 eccentrics 321 are mounted on the shaft 308, one eccentric being allotted to each outlet. The levers 271 bear upon these eccentrics, and as the shaft 308 rotates, the eccentrics 321 move the levers 271 and, thereby, the sliding 55

member 121 with the valve spindles 131. As a result of the rotation of the shaft 308 the valves of all the outlets are thus operated conjointly, being shifted from the closed position to that of maximum opening. The opening of the valves can now be adjusted by loosening the lock-nuts 241 and displacing the bolts 211. In this way the levers 271 have their leverage ratios modified. In order to provide adequate accommodation for the levers 271 and the eccentrics 321, the casing 101 is widened at the points opposite the flanges 208. The opening of the valves can be regulated independently of each other, and the adjustment may be carried out even when work is in progress. This enables the amounts flowing through the separate valves to be quantitatively balanced against each other with precision and to be adapted to the conditions prevailing.

The control member according to the invention has only a single packing gland, this being located at the spot where the shaft 308 passes through the cover 331. The functioning of the control member is thus very easily carried out more especially since, as in the present case, all moving parts run in oil.

I claim:

1. In a device of the class described, an oil receptacle having an outlet controlled by a valve, said valve having a threaded spindle, a threaded slide member adjustable on the threaded valve spindle, a pin carried by said slide member, a cam shaft mounted in the receptacle and having

a cam, and an oscillating lever actuated by said cam and having a longitudinal slot for engagement with said pin.

2. In a device for controlling the supply of oil and air in oil furnaces, an oil receptacle having an outlet and a guideway surrounding said outlet, a valve for controlling flow through said outlet, said valve having a slide member within the receptacle and adjustable on the valve spindle, a pin on the slide member, an actuating lever engageable with the pin, said slide member being slidable in the guideway surrounding the outlet, and an inflow aperture provided in the wall of the guideway.

3. In a device of the class described, an oil receptacle having an outlet, a guideway surrounding the outlet and an opening opposite the outlet and guideway, a valve controlling flow through the outlet and having a threaded spindle within the receptacle, a threaded slide member adjustably mounted on the spindle and having a pin, an actuating lever engageable by the pin, a spring engageable with the slide member for shifting the same, a plug for closing the opening and forming a stop for one end of the spring, said plug having a bore, and a screw closing the bore, said screw being removable for permitting access to the valve spindle whereby readjustment of said valve spindle with respect to the slide member may be effected.

EDWIN SPRENGER.
